FURNACE

Luis de Florez, Pomfret, Conn., assignor to The Texas Company, New York, N. Y., a corporation of Delaware

Application April 16, 1929, Serial No. 355,600

34 Claims. (Cl. 196—110)

My invention relates to furnaces, more particularly to tubular oil heaters used in processes involving the heating or cracking of oils, and has for its principal object the provision of a furnace 5 of this type by means of which a liquid such as oil can be thoroughly heated in a minimum of time, the apparatus therefore taking up but a relatively small amount of space.

The use of tubular oil heaters has developed 10 rapidly in recent years, due to the fact that adequate turbulence can be attained in these tubes by high velocity and that the surface can be disposed at will to permit comparatively even distribution of heat. In tubular heaters, especially 15 where economizers are used which consist of tubes placed across the flue to be heated by the outflowing gases, it has been difficult to maintain the gases at a velocity which will insure sufficient draft through the heater. One of the features of 20 my invention lies in the construction of an economizer, wherein provision is made for increasing the velocity of the gases as they pass through the flue.

In carrying out my invention in one form, 25 with the above objects in view, I have provided a tubular oil heater which comprises what may be termed a main radiant section, a secondary radiant section, and an economizer section. The main radiant section is constructed in the form of 30 a vertical cylindrical shell, the walls of which are lined with vertically disposed tubes. Fuel is admitted to a burner located at one end of the vertical chamber and the products of combustion are discharged at the other end and carried to the 35 economizer section through a horizontal flue. In this horizontal flue is arranged a second unit of tubes positioned so as to be subjected to the hot gases or products of combustion passing to the economizer. This last mentioned unit may 40 be termed a secondary radiant heater. The economizer consists of a series of horizontal tubes arranged at right angles to the path of the gases. A plurality of horseshoe-shaped strips are 45 hung over certain of the tubes in a manner to reduce the size of the passage progressively toward the upper tubes whereby the velocity of the gases is increased as the gases pass through the economizer.

My invention will be better understood from the 50 following description taken in connection with the accompanying drawings and its scope will be pointed out in the appended claims.

In the drawings Fig. 1 is a side elevation in section through a furnace embodying my invention; 55 Fig. 2 is a sectional elevation through the econo-

mizer and secondary radiant section, and Fig. 3 is an enlarged section through some of the economizer tubes.

Referring to the drawings, I have illustrated a furnace comprising a main radiant heating section 5 10, a secondary radiant heating section 11 and an economizer 12. A metallic wall or shell 13, preferably cylindrical in shape, defines the main heating chamber 14, the sides of this chamber being lined with suitable heat insulating, refractory 10 material 15. The wall or shell 13 is supported by a suitable framework 16 resting on bases 17. An arch 19 of heat insulating material forms a major part of the upper wall of the chamber 14, this arch being supported by suitable radial members 19a from the framework 16. Located upon the arch 19 and directly over the center of the cylindrical chamber 14 is a burner 20, and suitable inlets 21 and 22 may be provided respectively for the gas and oil, while a third inlet 23 allows 20 the admission of compressed air to the burner. Since the particular type or form of burner does not form part of my invention, I have shown this 25 diagrammatically only. At the center of the lower portion of the chamber 14 and directly opposite the burner 20 is an outlet flue 24, leading downwardly and then horizontally to the lower part of the economizer 12. It will thus be observed that upon the admission of fuel and air to the burner and ignition thereof, a flame will be 30 produced and directed downwardly through the center of the chamber 14, the hot gases of combustion therefrom passing into the flue 24.

In order to use to the fullest extent the radiant heat produced by the flame in chamber 14, I 35 have provided a plurality of tubes 25 arranged vertically in a pair of concentric circles around the periphery of the heating chamber 14. The tubes 25 are preferably supported or suspended from their upper extremities from a flat annular tube 40 sheet 26, this tube sheet 26 resting at its inner edge upon the arch 19 and at its outer edge upon the refractory lining 15, thus forming the remaining part of the top wall of the chamber 14. The upper and lower ends of adjacent tubes 45 25 are connected together by means of return bends 28 in a manner such that a continuous path for liquid to be heated is formed through the tubes. In other words, the liquid to be heated enters one of the tubes 25 through an inlet pipe 29 50 and then passes from tube to tube around the chamber 14, finally leaving the tubes through an outlet 30. While I have illustrated and described the tubes as being connected in series, it is to be understood that they may be connected in parallel 55

or in series parallel; i. e., all of the tubes may be connected between one pair of headers so that the liquid will pass through them all in the same direction at the same time, or small groups of the tubes may be connected in parallel and these groups connected in series.

Annular discs of heat insulating material 31 form part of the lower wall of the chamber 14 and serve to hold the tubes 25 in proper spaced relation. An annular cover member 36 rests upon the framework supporting the arch 19 directly above the tubes 25, and by removing this cover member access may be had to the tubes 25 for cleaning purposes or for removal and replacement of the tubes. That portion of the furnace described up to this point is substantially the same as described in my co-pending application, Serial Number 120,067, filed July 2, 1926, now U. S. Patent 1,717,334, issued July 11, 1929.

The horizontal part of the outlet flue 24 is preferably circular in section and is lined with a layer of suitable heat insulating material 37. The outer end of the horizontal flue 24 opens upwardly into the economizer 12. In the lower half of the flue 24 is arranged a plurality of tubes 38 extending horizontally and arranged preferably in the form of a semi-circle as is shown more clearly in Fig. 2. These tubes 38 are interconnected at their ends, thus forming a continuous passage for the liquid entering one of the tubes from the economizer. In the arrangement illustrated, the liquid having been preheated in the economizer, passes through the tubes 38 in the flue 24, then through the pipe 29 to the tubes 25 in the main radiant heating section and finally out of the heater through the pipe 30. The tubes 38 will thus be heated by the hot gases passing through the flue both by radiation and by partial convective contact. The horizontal unit of tubes may thus be termed a secondary radiant heating section.

A plurality of tubes 39 are supported horizontally in the heating chamber of the economizer and liquid entering these tubes through an inlet 40 passes downwardly through the tubes to an outlet 41, the liquid in the passage thus absorbing heat from the hot gases passing upwardly through the economizer around the tubes. A flue 42 at the top of the economizer preferably leads to a stack (not shown) and a pair of dampers 43 in this flue are adapted to control the draft through the economizer. A door 44 at each end of the horizontal flue 24 provides access to the interior.

In order to increase the velocity of the hot gases passing upwardly through the economizer 12, I have provided a plurality of metallic strips 45, each strip being bent into the shape of a horseshoe or hair pin. These strips 45 are hung upon and depend from the tubes 39 and are thus directly in the path of the hot gases. The number of strips increases progressively toward the top of the economizer, as will be observed with reference to Fig. 2 and hence it will be evident that the space through which the hot gases pass in traveling through the economizer decreases in inverse proportion to the increase in number of the strips 45. The velocity of these gases will thus be increased as the gases flow upwardly through the economizer. Since the strips 45 are of metal, they aid considerably in transferring heat from the gases to the tubes 39.

The use of the tubes 38 in the flue 24 provides for additional radiant surface and also facilitates 75 the connection between the outlet of the econo-

mizer 12 and the inlet of the vertical tubes 25. The bent strips 45 provide a simple and effective means for increasing the velocity of the flue gases in the economizer and thus materially increase the efficiency of the furnace.

While I have described my invention as embodied in concrete form in accordance with the provisions of the patent statutes it should be understood that I do not limit my invention thereto, since various changes and modifications 10 may be made without departing from the scope of the invention as defined by the accompanying claims.

What I claim is:

1. The method of heating hydrocarbon fluid 15 to elevated temperature, which comprises generating hot combustion gases, flowing hot combustion gases through a plurality of heating zones, in one of said zones applying heat to said fluid from said gases preponderantly by convection, 20 in another of said zones disposed substantially entirely below the point of generation of said hot gases and the point of entry and withdrawal of said gases passing therethrough, exposing substantially all of said fluid in said other zone to 25 radiant heat derived directly from said gases and heating said fluid preponderantly by radia-

tion.

2. The method of heating hydrocarbon fluid 30 to elevated temperature, which comprises generating hot combustion gases, flowing hot combustion gases through a furnace, in an upper zone of said furnace applying heat derived from said gases to the petroleum by convection, and in another zone of said furnace, below the first- 35 named zone and below the point of generation of said gases and the point of entry and withdrawal of said gases passing through said other zone, exposing substantially all of said petroleum in said other zone to radiant heat derived directly 40 from said gases and heating said petroleum preponderantly by radiation and thereby limiting the temperature rise of the petroleum in said first-named zone.

3. The method of heating hydrocarbon fluid 45 to elevated temperature, which comprises generating hot products of combustion, flowing said hot products of combustion through different heating zones, passing a stream of hydrocarbon fluid through one of said zones and therein applying heat derived from said gases flowing there- 50 through to said stream by convection, passing said stream through another of said heating zones in a path substantially entirely below the point of generation of said hot products of combustion and the point of entry and withdrawal of said hot products of combustion flowing through said other zone, and exposing substantially all of said fluid in said other zone to radiant heat derived directly from said hot products 55 of combustion and heating said fluid preponderantly by radiation.

4. The method of heating hydrocarbon fluid to elevated temperature, which comprises generating hot products of combustion in a sep- 65 arate combustion zone wherein at least partial combustion takes place, flowing said hot products of combustion through different heating zones, passing a stream of hydrocarbon fluid through one of said zones and therein applying 70 heat derived from said gases flowing there- through to said stream by convection, passing said stream through another of said heating zones in a path substantially entirely below the point of generation of said hot products of com- 75

- bustion and the point of entry and withdrawal of said hot products of combustion flowing through said other zone, and exposing substantially all of said fluid in said other zone to radiant heat derived directly from said hot products of combustion and heating said fluid preponderantly by radiation.
5. Oil heating apparatus for heating oil to conversion temperature comprising separate heat-absorption structures for conveying oil being heated disposed in different zones, means for producing a current of hot combustion gases through said zones in series and for heating the absorption structure in one of said zones by convection, the heat-absorption structure of another of said zones disposed substantially entirely below said means for producing said hot gases and the point of entry and withdrawal of gases with substantially all of said second-mentioned heat-absorption structure being exposed directly to radiation from said gases and heated preponderantly by radiation.
10. Oil heating apparatus for heating oil to conversion temperature comprising separate heat-absorption structures disposed in different zones, means for producing a current of hot combustion gases for passage through said zones in series and for heating the absorption structure in one of said zones by convection, bare tubular heat-absorption structure, in another of said zones, horizontally disposed below substantially the entire convectively heated absorption structure and said means for producing said hot gases and substantially entirely below the point of entry and withdrawal of combustion gases passing through said last-mentioned chamber, with substantially all of said last-mentioned heat-absorption structure being exposed directly to radiation from said gases and heated preponderantly by radiation, and means for connecting said absorption structures for passage of the oil therethrough in succession.
15. Oil heating apparatus for heating oil to conversion temperature comprising separate heat-absorption structures disposed in different zones, means for producing a current of hot combustion gases through said zones in series and for heating the absorption structure in one of said zones by convection, the heat-absorption structure of another of said zones horizontally disposed substantially entirely below said means for producing said hot gases and the point of entry of gases therein and substantially entirely below the point of withdrawal of gases therefrom, with substantially all of said last-mentioned heat-absorption structure being exposed directly to radiation from said gases and heated preponderantly by radiation, and means for conducting the oil from the heat-absorption structure in one of said zones to the heat-absorption structure in the other of said zones.
20. Oil heating apparatus for heating oil to conversion temperature comprising a heating chamber, means for introducing combustion gases into said chamber to effect a current of hot gases through said chamber, said chamber arranged to cause said combustion gases to flow through a substantial part thereof in a substantially rectilinear flow, heat-absorption structure in another chamber receiving said gases from the first-mentioned chamber adapted to absorb heat by convection from said gases, and means for reducing the temperature of said gases to prevent excessive temperature of said heat-absorption structure comprising heat-absorption structure horizontally disposed in said first-mentioned chamber substantially entirely below said means for introducing combustion gases and the point of entry and withdrawal of said combustion gases passing through said first-mentioned chamber with substantially all of said heat-absorption structure being exposed directly to radiation from said gases and absorbing heat preponderantly by radiation, and means for connecting said heat-absorption structures for passage of the oil therethrough in succession.
25. Oil heating apparatus for heating oil to conversion temperature comprising a plurality of chambers, means for producing a current of hot gases through said chambers in succession, oil-conducting tubes disposed in one of said chambers to absorb heat from said gases preponderantly by convection, and oil-conducting tubes, connected to said first-named tubes, horizontally disposed adjacent the bottom of
- another of said chambers substantially entirely below said means for producing said hot gases and the point of entry and withdrawal of the current of gases, with substantially all of said second-mentioned oil conducting tubes being exposed directly to radiation from said gases and heated preponderantly by radiation.
30. Oil heating apparatus for heating oil to conversion temperature comprising separate heat-absorption structures disposed in different zones, means for producing a current of hot combustion gases for passage through said zones in series and for heating the absorption structure in one of said zones by convection, another of said zones being arranged to cause said hot combustion gases passing therethrough to flow through a substantial part thereof in a substantially rectilinear path, the heat-absorption structure of said last mentioned zone being disposed substantially horizontally and substantially entirely below said means for producing said hot gases and the point of entry and withdrawal of gases passing through said last-mentioned zone, with substantially all of said second-mentioned heat-absorption structure being exposed directly to radiation from said gases and heated preponderantly by radiation.
35. A furnace for heating hydrocarbon fluid to conversion temperature comprising a heating chamber, means for producing hot gases for passage through said chamber, another heating chamber traversed by said hot gases, heat-absorption structure disposed in said second-mentioned heating chamber to receive heat from the gases by convection, another heat-absorption structure disposed in said first-mentioned heating chamber substantially entirely below said means for producing hot gases and the point of entry and withdrawal of said hot gases passing through the first-mentioned heating chamber with substantially all of said last-mentioned structure being exposed to radiation from said gases and heated preponderantly by radiation, and means for connecting said heat-absorption structures for passage of the fluid to be heated.
40. In a furnace for heating hydrocarbon fluids to conversion temperature, a heating chamber, means for producing hot combustion gases for passage through said heating chamber, conduit elements for conveying hydrocarbon fluid being heated in said heating chamber disposed substantially entirely below said means and the point of entry and withdrawal of said hot gases passing through said chamber, with substantially

all of said conduit elements being exposed directly to radiation from said gases and heated preponderantly by radiation, and other conduit elements for conveying hydrocarbon fluid being 5 directly exposed to said hot combustion gases and heated preponderantly by radiation.

13. In a furnace for heating hydrocarbon oils to conversion temperature, a radiant heating section, heat-absorbing tubes therein for conveying oil to be heated, means for producing hot products of combustion to heat said tubes by radiant heat, another radiant heating section positioned below said combustion producing means and in communication with said first- 10 mentioned heating section for the passage of hot products of combustion, separate heat-absorbing tubes for conveying oil being heated within said second-mentioned heating section horizontally disposed substantially entirely below 15 the means for producing hot products of combustion and the point of entry and withdrawal of said products of combustion passing through said second-mentioned heating section, with at least a part of said tubes being adjacent the 20 floor and with substantially all of them being exposed directly to radiation from said products of combustion and heated preponderantly by radiant heat, and means for connecting the 25 heat-absorbing tubes in one section to those of the other heating section.

14. In a furnace for heating hydrocarbon oils to conversion temperature; a heating section, heat-absorbing tubes therein adapted to be heated by radiation, another heating section below 30 said first-mentioned heating section, means for producing hot products of combustion for passage through said heating sections, separate heat-absorbing tubes in said second-mentioned heating section horizontally disposed substantially 35 entirely below said combustion producing means and the point of entry and withdrawal of said hot gases passing through the second-mentioned heating chamber, with at least a part of said tubes being adjacent the floor and with substantially all of them being exposed directly to radiation 40 from said products of combustion and heated preponderantly by radiant heat, and means for connecting the heat-absorbing tubes in one section to those of the other heating section.

15. In a furnace for heating hydrocarbon oils to conversion temperature, a combustion chamber having means for producing hot products of combustion associated therewith, a heating chamber connected to said combustion chamber 45 for receiving hot products of combustion therefrom for passage therethrough and conduit elements for conveying oil being heated in said heating chamber disposed substantially entirely below said means for producing hot products of combustion and the point of entry and withdrawal of hot products of combustion passing through said heating chamber with substantially all of said conduit elements being exposed directly to radiation from said products of combustion and heated preponderantly by radiation.

16. A system for transferring heat to a hydrocarbon fluid passed through heat-absorption structures to be heated therein to conversion temperature, comprising a combustion chamber, 50 means for producing hot gases associated with said combustion chamber, a heating chamber into which said combustion chamber discharges hot gases, another heating chamber extending upwardly above the outlet of said combustion chamber and traversed by said hot gases, heat-

absorption structure disposed in said second-mentioned heating chamber to receive heat from the gases by convection, a separate floor tube section disposed in said first-mentioned heating chamber substantially entirely below said means 5 for producing said hot gases and the point of entry and withdrawal of said hot gases passing through the first-mentioned heating chamber with substantially all of said floor tube section being exposed directly to radiation from said 10 gases and heated preponderantly by radiation, and means for connecting said floor tube section and heat-absorption structure for passage therethrough of the fluid to be heated.

17. A system for transferring heat to a hydrocarbon fluid passed through heat-absorption structures to be heated therein to conversion temperature, comprising a combustion chamber, means for producing hot gases associated with said combustion chamber, a heating chamber 20 into which said combustion chamber discharges hot gases, another heating chamber traversed by said hot gases, heat-absorption structure disposed within said second-mentioned chamber in the current of gases to receive heat therefrom 25 preponderantly by convection, a separate floor tube section disposed in said first-mentioned heating chamber substantially entirely below said means for producing said hot gases and the point of entry and withdrawal of said hot gases 30 passing through the first-mentioned heating chamber with substantially all of said floor tube section being exposed directly to radiation from said gases and heated preponderantly by radiation, and means for connecting said floor tube 35 section and heat-absorption structure for passage therethrough of the fluid to be heated.

18. In a furnace for heating hydrocarbon oils to conversion temperature, a combustion chamber having means for producing hot products of combustion associated therewith, a heating chamber connected to said combustion chamber for receiving hot products of combustion therefrom for passage therethrough, conduit elements for conveying oil being heated in said heating chamber and horizontally disposed substantially 40 entirely below said means for producing said hot products of combustion and the point of entry of hot products of combustion passing therethrough and substantially entirely below the point of withdrawal of products of combustion therefrom, with substantially all of said conduit elements being exposed directly to radiation from said gases and heated preponderantly by radiation, another heating chamber connected to said 45 first-mentioned heating chamber for receiving products of combustion therefrom, and conduit elements in said last-mentioned heating chamber connected to said conduit elements in said first-mentioned heating chamber to be heated 50 preponderantly by convection heat from said hot products of combustion.

19. In a furnace for heating hydrocarbon oils to conversion temperature, a combustion chamber having means for producing hot products of combustion associated therewith, a heating chamber connected to said combustion chamber for receiving hot products of combustion therefrom, said heating chamber arranged to cause said hot products of combustion to flow through 70 a substantial part of said heating chamber in a substantially rectilinear path, and horizontally disposed conduit elements for conveying oil being heated in said heating chamber arranged in parallel relationship to each other and disposed sub- 75

- stantially entirely below said means for producing said hot products of combustion and the point of entry and withdrawal of hot products of combustion passing through said heating chamber with substantially all of said conduit elements being exposed directly to radiation from said gases and heated preponderantly by radiation.
20. In a furnace for heating hydrocarbon oils to conversion temperature, a combustion chamber having means for producing hot products of combustion associated therewith, a heating chamber connected to said combustion chamber for receiving hot products of combustion therefrom, said heating chamber arranged to cause said hot products of combustion to flow through a substantial part of said heating chamber in a substantially rectilinear path, conduit elements for conveying oil being heated in said heating chamber and horizontally disposed substantially entirely below said means for producing said hot products of combustion and the point of entry and withdrawal of hot products of combustion passing through said heating chamber with substantially all of said conduit elements being exposed directly to radiation from said gases and heated preponderantly by radiation, another heating chamber connected to said first-mentioned heating chamber for receiving products of combustion therefrom, and conduit elements in said heating chamber connected to said first-mentioned heating chamber to be heated preponderantly by convection heat from said hot products of combustion.
35. 21. A system for heating petroleum to conversion temperature comprising a chamber arranged to cause combustion gases to flow through a substantial part thereof in a substantially rectilinear flow, a combustion chamber discharging combustion gases into said chamber, means for producing hot gases associated with said combustion chamber, heat-absorbing structure in said first-named chamber horizontally disposed substantially entirely below said means for producing said hot gases and the point of entry and discharge of gases passing through said first-mentioned chamber, with substantially all of said heat-absorption structure being exposed directly to radiation from said gases and heated preponderantly by radiation, another heat-absorbing structure in said system to absorb heat by convection from said combustion gases, and connections for passing the petroleum through said heat-absorbing structures in succession.
55. 22. A system for transferring heat to hydrocarbon fluid to raise said fluid to conversion temperature comprising a chamber arranged to cause combustion gases to flow through a substantial part thereof in a substantially rectilinear flow, a combustion chamber discharging combustion gases into said chamber, means for producing hot gases associated with said combustion chamber, heat-absorption structure horizontally disposed in said first-named chamber comprising tubes, at least some of which are adjacent the discharge of said combustion chamber and all of which are substantially entirely below said means for producing said hot gases and the point of entry and discharge of said hot gases passing through said first-mentioned chamber, with substantially all of said heat-absorption structure being exposed directly to radiation from said gases and heated preponderantly by radiation, heat-absorption structure in another zone of the system adapted to absorb heat by convection from said combustion gases, and means for connecting said heat-absorption structures for passage of the fluid therethrough in succession.
5. 23. A system for heating petroleum to conversion temperature, comprising a housing structure enclosing a plurality of heating zones, a plurality of heat-absorption structures disposed in different of said zones, means for connecting said absorption structures for passage of the petroleum therethrough in succession, a combustion chamber discharging hot combustion gases through said zones in succession, means for producing hot gases associated with said combustion chamber, a heat-absorption structure in one of said zones adapted to be heated by convection, and tubular heat-absorption structure in another of said zones, disposed substantially entirely below said means for producing said hot gases and the point of entry and withdrawal of the stream of gases passing through said other zone, with substantially all of said tubular heat-absorption structure being exposed directly to radiation from said gases and heated preponderantly by radiation.
25. 24. Heat transfer apparatus for heating hydrocarbon fluid to conversion temperature comprising means for producing combustion gases, a heating chamber traversed by combustion gases, heat-absorption structure for conveying said fluid being heated disposed in said chamber, another heating chamber traversed by combustion gases, other heat-absorption structure for conveying said fluid being heated with at least a part thereof disposed adjacent the bottom of said last-mentioned chamber and with all of it disposed substantially entirely below said means for producing said combustion gases and the point of entry and withdrawal of said combustion gases passing therethrough, with substantially all of said heat-absorption structure being exposed directly to radiation from said gases and heated preponderantly by radiation and so disposed differently, in relation to the gas flow, from said first-named absorption structure that it absorbs sufficient heat materially to reduce the temperature of said gases for protection of said first heat-absorption structure, and means comprising a chamber for effecting at least partial combustion before introduction of said gases into said second-mentioned heating chamber.
35. 25. Fluid heating apparatus for heating hydrocarbon fluid to conversion temperature comprising a combustion chamber, means for producing hot gases associated with said combustion chamber, a heating chamber receiving hot gases formed in said combustion chamber, heat-absorption structure disposed in said heating chamber to receive heat by convection from the gases, another heating chamber in communication with the discharge end of the combustion chamber, heat-absorption structure in said last-mentioned heating chamber horizontally disposed adjacent the discharge end of the combustion chamber and substantially entirely below said means for producing said hot gases and the discharge end of said combustion chamber and the point of withdrawal of said hot gases from the first-mentioned heating chamber, with substantially all of said last-mentioned heat-absorption structure being exposed directly to radiation from said gases and absorbing heat preponderantly by radiation, for limiting the temperature to which the first-named heat-absorption structure is subjected.

and means connecting said absorption structures for passage of fluid therethrough in succession.

26. In a furnace comprising a vertically arranged substantially cylindrical combustion chamber, a heating coil composed of a plurality of vertically disposed interconnected heat absorbing tubes adjacent to the wall of the combustion chamber and disposed on an annular pitch circle, the center of which substantially corresponds with the center of the combustion chamber, means for directing burning fuel and the products of combustion thereof in a central longitudinal and unobstructed path through said chamber and substantially out of contact with said tubes, an insulated flue section free from heat absorbing tubes and leading from the lower part of said combustion chamber, an outlet flue connected with said flue section, and a plurality of tubes arranged longitudinally around part of the inner circumference of said outlet flue, said latter tubes being connected to said first mentioned tubes and forming a secondary heat absorbing unit.

27. In a furnace, a substantially cylindrical vertical combustion chamber, a heating coil composed of a plurality of vertically disposed interconnected heat absorbing tubes adjacent to the wall of the combustion chamber and disposed on an annular pitch circle the center of which substantially corresponds with the center of the combustion chamber, a burner located at one end of the chamber so positioned centrally with respect to said tubes as to impel its flame and the products of combustion in an unobstructed vertical path substantially parallel to and out of direct contact with said tubes, an insulated flue section free from heat absorbing tubes and leading from the end of said combustion chamber opposite to said burner, a horizontal outlet flue connecting with said flue section, and a plurality of tubes arranged longitudinally in the shape of a semi-circle in the lower part of said outlet flue and forming a secondary heat absorbing unit.

28. In a furnace for heating oil, walls defining a substantially cylindrical heating chamber, a plurality of tubes arranged vertically around the inner periphery of said walls, means located in the upper central portion of said chamber for producing and directing downwardly a high temperature radiant flame whereby radiant heat may be absorbed by said tubes, an insulated flue section free from heat absorbing tubes leading from the lower part of said chamber, a horizontal outlet flue connecting with said flue section, and a plurality of tubes arranged longitudinally in the shape of a semi-circle in the lower part of said outlet flue and adapted to be heated by said hot gases, thereby forming a secondary radiant heat absorbing unit.

29. A furnace comprising a vertical heating section, a horizontal heating section, an economizer chamber, a plurality of interconnected heat absorbing tubes in said heating sections and economizer chamber, means for projecting a flame into said vertical section, means for directing the hot products of combustion through said horizontal section and through said economizer chamber, and separate insulated flue sections connecting said vertical section and said horizontal section, and said horizontal section and said economizer chamber, respectively.

30. In a furnace comprising a vertically arranged substantially cylindrical combustion chamber, a heating coil composed of a plurality of vertically disposed interconnected heat ab-

sorbing tubes adjacent to the wall of the combustion chamber and disposed on an annular pitch circle, the center of which substantially corresponds with the center of the combustion chamber, means for directing burning fuel and the products of combustion thereof in a central longitudinal and unobstructed path through said chamber and substantially out of contact with said tubes, an insulated flue section free from heat absorbing tubes and leading from the lower part of said combustion chamber, an outlet flue connected with said flue section, and a plurality of heating tubes all arranged longitudinally within said outlet flue and connected to said first mentioned tubes, forming a secondary heat absorbing unit.

31. A furnace for heating oil, comprising walls forming a down draft radiant heating chamber, an insulated flue section free from heat absorbing tubes and leading from the lower part of said heating chamber, an outlet flue connecting with said flue section and extending substantially at right angles to said chamber, an economizer chamber, a second insulated flue section free from heat absorbing tubes connecting said economizer chamber and said outlet flue, means for directing a flame downwardly in said heating chamber, a series of heat absorbing tubes in said heating chamber, outlet flue and economizer chamber through which the oil to be heated passes in a reverse direction to the direction of flow of said flame and the hot products of combustion, and means associated with some of the tubes in said economizer chamber for progressively increasing the velocity of the products of combustion passing through said economizer.

32. In a furnace, a heating chamber, heat absorbing tubes therein, heat producing means for heating said heat absorbing tubes by radiant heat, an insulated flue section leading from one end of said heating chamber, another heating chamber connected with said flue section, and a plurality of heat absorbing tubes connected to said first mentioned tubes disposed longitudinally around the surface of said last mentioned heating chamber and adapted to be heated by radiant and partial convection heat.

33. In a furnace, a heating chamber, heat absorbing tubes therein, heat producing means for heating said heat absorbing tubes by radiant heat, an insulated flue section leading from one end of said heating chamber, another heating chamber connected with said flue section, and a plurality of heat absorbing tubes connected to said first mentioned tubes disposed longitudinally around a portion of the surface of said last mentioned heating chamber and adapted to be heated by radiant and partial convection heat.

34. In a furnace, a heating chamber, heat absorbing tubes therein, heat producing means for heating said heat absorbing tubes by radiant heat, an insulated flue section leading from one end of said heating chamber, another heating chamber connected with said flue section, and a plurality of heat absorbing tubes connected to said first mentioned tubes disposed longitudinally around a portion of the surface of said last mentioned heating chamber and adapted to be heated by radiant and partial convection heat, and an economizer section having heat absorbing tubes therein connected to said second mentioned heating chamber, the aforementioned heat absorbing tubes being connected to form a continuous path for a fluid to be heated.
